UNITED STATES PATENT OFFICE.

LYNN EVANS, OF CORTLAND, NEW YORK, ASSIGNOR TO THE BREWER-TITCHENER CORPORATION, OF CORTLAND, NEW YORK, A CORPORATION OF NEW YORK.

METHOD OF CONSTRUCTING SHEATHED FILLER MEMBERS.

Application filed February 29, 1924. Serial No. 696,003.

To all whom it may concern:

Be it known that I, LYNN EVANS, a citizen of the United States, and a resident of Cortland, in the county of Cortland and 5 State of New York, have invented certain new and useful Improvements in a Method of Constructing Sheathed Filler Members, of which the following is a specification.

My invention relates to a novel constructive method for making metal encased core or filler blocks, and particularly such as pertain to the production of an improved type of composite bow as applied to a vehicle top frame. The object of my invention 10 is to provide an improved method for constructing bows and like structures wherein a laminated fibrous filler member is covered with a sheet metal sheath conforming to the cross-sectional contour of the filler block. 20 The laminated wood-like filler member is preferably cut into a uniform rectangular shape and this is fully encased on three of its sides by means of a suitable bent channel shaped sheet metal sheath strip. The projecting edges of said strip are further crimped inwardly over the fourth side of said filler to constitute a peripherally incomplete tube. The longitudinal sheath edges are spaced 25 apart so as to form a slot or access gap there- 30 between which allows of convenient access to the filler block for tacking purposes throughout the length of the bow. Underlying the spaced wing or edge portions of said sheath and serving to span said slot, I provide for 35 a bridge strip lamination which may be made either of the same or different material from that used for the remainder of the laminated filler but is preferably made of suitable sheet material such as fibre or the like which completes said tubular sheath enclosure. 40

The component parts are initially formed in straight sectional lengths, and when assembled, the encased laminated wood-like 45 filler may readily be bent cold without the need of a steaming process to give the filler increased pliability. By the use of said bridge strip in association with said other laminated core, the filler block is less liable 50 to sliver or check while being bent into any desired shape for the reason that the separate laminations tend to slip over each other while the complete confinement of the filler by the outermost lamination or bridge strip, 55 brings a counter pressure to bear against all

sides of the filler block. Furthermore, in the event that the interior or concealed fibrous fillers should show signs of excessive slivering, the resulting splinters are held snugly encased and prevented from projecting outward from the sheath enclosure by the protective armor afforded by said bridge strip. 60

As applied to transverse bows for vehicle top frames, it is preferred to make the bridge strip either of perforated metal or of heavy card-board and similar fibrous sheet material that may readily be penetrated by means of tacks or nails for the purpose of securing the vehicle deck fabric parts to the 65 filler blocks of my improved type of bow 70 while the sheath proper is left imperforate except for its characteristic accessory gap. The provision of a bridge strip affords substantially the same advantages as to bending the encased filler block as does a completely closed metal sheath but without destroying the accessory tacking feature thereof. 75

Embodied herein are also further features of structure adapted to facilitate the application and forming of said filler sheaths and bridge strips therefor, all of which will be set forth hereinafter. 80

For a more detailed description of my invention, reference is had to the accompanying one sheet of drawings which illustrate an example of its preferred embodiment; like characters of reference indicate like parts in the several views, and in which drawing: 85

Fig. 1, illustrates an elevational view of a metal encased wooden filler block, taken in section lengthwise of a bent or knee element of a transverse bow as used for vehicle top frames. 90

Fig. 2, represents a cross-sectional view as taken along the line 2—2 of Fig. 1 to show in further detail the rectangular filler block together with an incomplete sheath therefor and a bridge strip spanning said 100 gap.

Fig. 3, indicates an elevational view of a permanent top frame for a vehicle deck and the method of applying a bent transverse bow to the side rails thereof. 105

Fig. 4, represents a partial perspective view illustrating a bent bow or knee element similar to Fig. 1, but showing a modification in the type of bridge strip used therefor. 110

Fig. 5, is a cross-sectional view of the knee elements as taken along line 5—5 of Fig. 4.

Fig. 6, represents a modified structure for the filler blocks and shows the use of a larger plurality of laminated filler strips encased by the metal sheath than is shown in the other figures.

Referring first to Fig. 3, showing an embodiment of my invention as applied to a transverse vehicle bow, which bow comprises a crown or longitudinal element A₁, the end portions of which are provided with the legs B₁ and B₂, as formed by the corner or knee elements C₁ and C₂, respectively. The legs of this bow are suitably fastened to a pair of complementary side rails such as D₁ and D₂, which are intended to be supported over the vehicle body and covered by means of a deck fabric in the conventional manner.

The subject matter of the present invention more largely resides in improved method of making the knee elements of said bows or like structures in the manner illustrated in detail by Figs. 1 and 2.

The wood filler block C₁₀ of the knee section such as C₁, is preferably but not necessarily made in a cross-sectionally rectangular shape as shown. This filler may comprise two or more laminations including the bridge strip, which are almost wholly encased by the metal sheath C₁₁, and said filler preferably extends along the entire bow length. Said sheath may initially be formed in substantially straight tubular length or section from a strip of soft sheet metal of suitable width adapted to snugly encase three sides of the laminated rectangular filler block C₁₀ and at the same time disposed about the fourth side of said block in such a manner as to provide for a longitudinal slot or access gap C₁₃ spaced between the inwardly crimped strip edges or wing portions of the sheath, designated as C₁₂. When rolled or drawn in one operation, the set of overhung wing parts C₁₂ as initially formed do not bear down against the fourth side of said filler C₁₀, but are held in a spaced relation thereto to provide room for inserting the bridge strip C₁₄ shown in Fig. 2.

This long narrow bridge strip C₁₄ serves to close the longitudinal gap C₁₃ and is preferably cut to fit the inside dimensions of the sheath width, whereby said strip edges are made to abut the side walls of said sheath and to fully underlie the two inturned wing portions C₁₂ of the sheath. After the various members are properly assembled, they may be run through a roll or press for the purpose of firmly crimping down both wings C₁₂ against the encased filler and bridge members.

As an alternative method for forming the filler casing, the straight sheath length may initially be rolled into a channel or trough

like cross-sectional shape. The filler block is then placed into the bottom of said channel with the bridge strip laid upon said block. The legs of the channel are purposely made sufficiently long to project beyond the adjacent filler sides to allow of crimping same over the edges of the assembled bridge strip and still provide for the gap C₁₃ between the inner edges of the in-turned channel legs.

Thereupon, the assembled filled sheath lengths may, if desired, be shaped or bent in a cold state transversely of the flat bridge strip, that is to say without prior steaming, to form relatively sharp curved or radius portions such as the bow knees C₁ and C₂, shown in Fig. 3. This operation may readily be performed by bending said assembled sheath over a suitable roll to form any reasonable radius desired. It is pointed out that the metal sheath serves to retain and hold the filler in the desired bent shape notwithstanding that the laminated elements of the filler proper may tend to return to their original shape.

As regards the material used as filler or core members for the sheath, these are preferably but not necessarily made of strips of wood such as straight grained slippery elm or red elm, white elm, ash or oak and the like. It is customary to thoroughly soak such woods in boiling water or to steam same for a protracted period in order to soften the wood fibers prior to bending same. Without the described provision for a complete sheath, and if bent in a cold state, the wood filler would tend to rupture and splinter badly, but by the use of the surrounding sheath and its complementary bridge strip, the filler can more readily be bent to conform to any reasonable radius required.

By virtue of the metal confining walls, the wood is less liable to splinter or crack, and furthermore, in the event that this should occur, the fibrous bridge strip serves to cover up and confine the splinters within the sheath enclosure so as to prevent bodily injury or other harmful effects in the use of bent bows or similar parts. In addition to providing for the described tacking facilities, the bridge strip C₁₄ also neatly covers any bending flaws in the filler and presents a smooth and trimmed appearance along its entire surface. It will be apparent that the bridge strip need not run along the entire length of the bow but if desired, may only be applied to the knee portions thereof.

A modified type of filler block over that previously described is shown in Fig. 6 in so far as the wood is laminated into a plurality of relatively thin strips such as C_{10a}, C_{10b} and C_{10c}, which together constitute a bundle of filler blocks. Such divided wood strips facilitate the bending operation and serve to

obviate checking or slivering, especially so when the combined or overall thickness of the filler strips should be excessive and beyond that suitable for a single or integral 5 filler block. It will be apparent that the use of a filler block and its superimposed bridge strip such as has been previously described in connection with Fig. 2, itself constitutes a laminated filler block for the composite 10 sheathed members. As applied to the transverse bow shown in Fig. 3, it will be understood that the plural filler strips are preferably run from end to end of said bow. The bridge strip C_{14} shown in Fig. 2, may 15 be made of any kind of material suitable for the purpose described; if desired, said strip may also be made of wood similar to the remainder of the filler block, but when used in connection with a transverse bow, it 20 is preferred to employ sheet fibre, heavy card or paste-board or similar non-fibrous sheet material therefor, since this prevents splitting and at the same time admits of easy penetration of same by means of tacks, 25 nails or the like. In such applications, the access gap 13 of the bow is preferably made to serve as a tacking slot for fastening the deck fabric of the vehicle top to the bow, the fabric being mounted over the exterior of 30 the bows and side rails in the conventional manner.

Similar results may be obtained by the use of a perforated bridge strip C_{15} such as is shown in Figs. 4 and 5. This modified 35 bridge strip is made of perforated sheet metal having closely spaced holes C_{16} which facilitate the penetration through said metal strip by tacks or other fastening means without having to pierce the sheath metal. A 40 close mesh wire screen may similarly be utilized as a bridge strip, but in all such cases the function is substantially identical with that of the fibrous material previously described in connection with the bridge strip 45 C_{14} . In Fig. 5, C_{17} illustrates a deck fabric for a vehicle top which is intended to cover the transverse bow and this may be secured to the wood filler C_{10} by means of suitably spaced tacks such as C_{18} , which pass through 50 the bridge strip in the manner indicated.

While the assembled sheathed filler blocks may be bent in a cold state as described in order to save the trouble and expense of steaming prior to bending, it will be evident 55 that when wholly encased within a metal sheath and bridge member, the wood filler proper may still be partially or fully steamed, should this step be desired. In certain cases, it may be expedient to resort 60 to a steaming process for the filler, especially when it is necessary to prevent all checking or rupture of the filler fibers or when it is preferred to utilize somewhat cheaper grades of wood filler blocks which are partially cross-grained or not entirely free from knots. 65

It will be apparent that the use of the reinforcing metal sheath imparts a large measure of strength to the enclosed filler block for any given external dimensions, and that this allows of making the parts considerably smaller and more compact as compared to an unsheathed wood bow or like parts. Furthermore, the described incomplete tubular sheath member may be readily and economically formed, and since the 70 bridge strip extends across and laterally braces the side walls of the tube adjacent to the gap C_{13} , this reenforcement practically brings the filler sheath up to its fully closed tubular strength. 75

It is pointed out that the sheath and its bridge strip need not necessarily be rectangular in cross-sectional shape, but instead these members may readily be given a circular or modified contour, if so preferred. 80 Furthermore, it is not essential for the longitudinal gap C_{13} to extend along the entire sheath length as described, and instead a series of suitably spaced openings cut into either edge of the sheath would 85 likewise serve accessory purposes. It will be understood therefore that the described sheath structure for filler blocks may readily be modified to serve different conditions and purposes, and that various changes in the 90 details of my method may be resorted to without departing from the spirit and scope of my invention, heretofore described and more particularly pointed out in the appended claims. 95

Claims:

1. The method of constructing composite members, which method consists of introducing within a longitudinally continuous but peripherally incomplete unitary sheet metal sheath, a laminated filler block including a bridge strip made of material differing from that in the remainder of said laminated block and adapted to cover and conceal said remaining laminations within 105 said incomplete sheath, said sheath being disposed to grip and hold together all the filler laminations without need of supplementary securing means. 110

2. The method of constructing bent composite members, which method consists of introducing within a longitudinally continuous but peripherally incomplete unitary sheet-metal sheath, a laminated wood-like or similar ingrained fibrous filler block 120 having the major portion of its superficial surface encased by said incomplete sheath and gripped thereby to hold together the filler laminations without need of supplementary securing means, and thereupon 125 bending the assembled composite member aforesaid.

3. The method of constructing bent composite members, which method consists of introducing within a longitudinally continu- 130

ous but peripherally incomplete sheet-metal sheath provided with an access gap between the longitudinal edges thereof, a laminated wood-like or similar ingrained fibrous filler block including a bridge strip which strip is disposed to underlie the longitudinal edges of said sheath and span said gap, and thereupon bending the composite members aforesaid transversely with respect to 10 the flat face of said bridge strip.

4. The method of constructing bent composite members, which method consists of introducing into the bottom of a cross-sectionally channel-shaped metal sheath, a 15 laminated wood-like or similar ingrained fibrous filler block, then crimping over both legs of said channel upon said filler to constitute a gap between the longitudinal edges of said sheath, and thereupon bending the 20 assembled composite members aforesaid into a knee or radius shape.

5. The method of constructing bent composite members, which method consists of introducing into a longitudinally continuous but peripherally incomplete sheet-metal sheath provided with an access gap between the edges thereof, a laminated filler block including a bridge strip which strip is disposed to underlie the spaced longitudinal 30 edges of said sheath, and is made of a material differing from that of the remainder of said laminated block, and thereupon bending the assembled composite members aforesaid.

35 6. The method of constructing bent composite members, which method consists of introducing within a longitudinal continuous but peripherally incomplete sheet metal sheath provided with an access gap between 40 the longitudinal edges thereof, a laminated

wood-like or similar ingrained fibrous filler block including a bridge strip which strip is disposed to underlie the longitudinal edges of said sheath and adapted for tacking an extraneous material to said laminated block through said gap, and thereupon bending the assembled composite members aforesaid.

7. The method of constructing bent composite bows, which method consists of introducing within a longitudinally continuous but peripherally incomplete sheet-metal sheath provided with an access gap through 50 said sheath, a laminated wood-like or similar ingrained fibrous filler block including a bridge strip which is superimposed upon the remainder of said laminated block and adapted to span said gap, and thereupon bending the end portions of the assembled composite bow member into a set of knees 55 60 to form the respective legs for said bow.

8. The method of constructing bent composite bows, which method consists of introducing within a longitudinally continuous but peripherally incomplete sheet-metal sheath provided with an access gap between the longitudinal edges thereof, a laminated 65 filler block of which one lamination consists of wood and another of penetratable material other than wood which latter lamination is superimposed upon said wood and adapted to underlie the longitudinal edges of said sheath, and thereupon bending the end portions of the assembled composite 70 75 bow members to form respective legs for said bow.

In testimony whereof, I have herewith set my hand this 28th day of February, 1924.

LYNN EVANS.
